UNITED STATES PATENT OFFICE.

JOSEPH P. LAVIGNE, OF DETROIT, MICHIGAN.

COLLAPSIBLE TAP.

1,190,561.

Specification of Letters Patent. Patented July 11, 1916.

Application filed November 22, 1913. Serial No. 802,354.

To all whom it may concern:

Be it known that I, JOSEPH P. LAVIGNE, a citizen of the United States of America, residing at Detroit, in the county of Wayne 5 and State of Michigan, have invented certain new and useful Improvements in Collapsible Taps, of which the following is a specification, reference being had therein to the accompanying drawings.

- 10 This invention relates to a collapsible tap for use on lathes, screw-machines, boring machines and the like whereby the dies are rigidly held to their work and whereby accurate adjustment is obtainable.
- 15 The invention also includes means that permit the work of the tool in a comparatively small opening and an adjustment or interchange of dies through a wide range.

The invention consists in the matters 20 hereinafter set forth and more particularly pointed out in the appended claims.

In the drawings, Figure 1 is a view, partially in elevation and partially in section, of a tap that embodies features of the invention; Fig. 2 is an end view thereof; Fig. 3 is a view taken in section on or about line III—III of Fig. 1; Fig. 4 is a view in section taken on or about line IV—IV of Fig. 1; Fig. 5 is a view that is partially in elevation and partially on the line of section V—V of Fig. 2; and Fig. 6 is a view in transverse section taken on or about line VI—VI of Fig. 1.

As herein shown, a main head 1 has a 35 shank 2 whereby it may be inserted in the tool carrying member of a screw-machine or the like. An outer casing 3 is detachably secured as by screws 4 to a flange of the head 1 and is appropriately apertured to 40 receive the cylindrical shanks 5 of tap dies arranged symmetrically around the axis of rotation of the casing.

The cutting edges of the dies are so disposed in eccentric relation to the axes of the 45 shanks that rotation of the dies throws them from or toward the axis of rotation of the head and the casing so as to make them operative or inoperative. This simultaneous rotation of the taps on their respective axes 50 is obtained through segmental gear teeth 6 on each meshing with an internal annular gear 7 that may be turned in respect to the

casing 3 by a suitable handle 8. The latter is held by suitable means 9 in frictional engagement with a cover strip 10 of the 55 casing.

The movement of the gear 7 by means of the handle 8 is opposed by a suitable spring 11 whose ends are respectively anchored to the head 1 and the gear 7 so as to operate 60 both as a torsion and compression spring. The spring holds the gear 7 interlocked with the ratchets 12 of a stop collar 13 when the dies are in cutting position. By means of a worm 14 the collar 13 may be shifted to 65 adjust the point of engagement so that the taps may be spread open to cut a thread of the required diameter. A check nut 16 and thrust screw 17 are used to effectively hold the worm 14 in position although other adjusting means may be employed if desired. The inner portion of the cylindrical stems 5 of the dies are screw-threaded to engage a bushing 24 that may be rotated in the head by means of a worm spindle 18 or the 70 like mounted similarly to the worm 14 and engaged by suitable teeth on the bushing. Rotation of the bushing 24 thus operates to simultaneously shift the dies longitudinally in or out as required. 80

A knock-off head 20 is in reciprocable engagement with a nipple 21 forming an outer portion of the casing. Thrust studs 23 connect the head 20 with the gear 7. When the knock-off head 20 encounters any gage or 85 part of the work to which the tap is applied so that it is moved backward, the gear moves out of engagement with the ratchets 12 and is snapped back to initial position by the action of the spring so as to turn the 90 dies out of operative position or into collapsed position. As a result of this construction the tap is available for use in narrow or restricted places as the knock-off and other operating mechanism are within the 95 outer limits of the tools. It is positive in its action and the tap members or the dies proper are supported for substantially their entire length to within a very short distance of their cutting edges. This insures 100 rigidity and freedom from vibration.

Obviously, changes in the details of construction may be made without departing from the spirit of my invention and I do

not care to limit myself to any particular form or arrangement of parts within the scope of the appended claims.

What I claim is:—

- 5 1. A collapsible tap comprising a main head, an outer casing mounted thereon, cutting dies journaled in the head and casing in symmetrical relation and around the axis of rotation, a member rotatable in the head
- 10 in engagement with the several dies for projecting them simultaneously from the head, a spindle in the head adapted to operate the die projecting means, a rotatable member in the casing adapted to simultaneously engage and turn the dies, a knock-off member on the casing engaging the die rotating member and adapted to reciprocate the latter longitudinally of the casing and a spring member in the casing adapted to yieldingly
- 15 20 project the dies and turning member against the thrust of the knock-off member and normally retain the die rotating members in initial position.

2. A collapsible tap comprising a main head, a casing thereon, cutting dies journaled in the head and casing in symmetrical relation to the axis of rotation, a bushing rotatable in the head in screwthreaded engagement with the several dies for projecting them simultaneously from the head, a worm spindle in the head adapted to turn the bushing, an annular gear journaled in the casing segmental teeth on the dies meshing with the annular gear, a handle for shifting the gear to turn the dies into operative position, a stop collar in the head adapted to interlock with the gear when the dies are in cutting position, a spring member in compression and tension between the head and annular gear adapted to normally hold the latter interlocked with the stop collar and to turn the latter when released from the stop collar to inoperative position, and a knock-off member adapted to shift the gear out of engagement with the stop collar.

3 A collapsible tap comprising a rotatable head, a casing on the head, cutting dies having cylindrical shanks journaled in the head and casing in symmetrical relation
50 with the axes of rotation and with cutting edges on the projecting portions eccentric to the shank axes, segmental gear teeth on the shank axes, a bushing rotatable in the head in screwthreaded engagement with the shank
55 for projecting the latter from the head, worm teeth on the bushing, a manually operable worm spindle in the head meshing with the bushing teeth, an annular gear journaled in the head and casing in mesh with
60 the teeth of the shanks, a stop collar rotatable in the casing and head adapted to interlock with the annular gear when the latter has turned the dies into cutting position, a manually operable worm spindle in the
65 head and casing in mesh with the teeth of

the stop collar, a spring member in the casing secured to the head and adapted to hold the gear in engagement with the stop collar and to turn the gear when released from the stop collar to inoperative position, and a knock-off member reciprocable on the casing adapted to shift the gear out of engagement with the collar. 70

4. A collapsible tap comprising a rotatable head, a casing on the head, cutting dies having cylindrical shanks journaled in the head and casing in symmetrical relation with the axis of rotation and with cutting edges on the projecting portions eccentric to the shank axes, segmental gear teeth on the shank axes, 80 a bushing rotatable in the head in screw-threaded engagement with the shanks for projecting the latter from the head, worm teeth on the bushing, a manually operable worm spindle in the head meshing with the 85 bushing teeth, an annular gear journaled in the head and casing in mesh with the teeth of the shanks, a stop collar rotatable in the casing and head adapted to interlock with the annular gear when the latter has turned 90 the dies into cutting position, a manually operable worm spindle in the head and casing in mesh with the teeth of the stop collar, a spring member in the casing secured to the head and adapted to hold 95 the gear in engagement with the stop collar and to turn the gear when released from the stop collar to inoperative position, a knock-off member reciprocable on the casing adapted to shift the gear out of engagement with the collar, and a manually operable member extending from the gear in frictional engagement with the casing for turning the gear into position to interlock 100 with the stop collar. 105

5. A collapsible tap comprising a rotatable head, dies having cylindrical shanks journaled in the head in symmetrical relation to the axis of rotation thereof, cutting edges in the dies in eccentric relation to the shank axes, gear teeth on each of the shanks, a bushing rotatable in the head in screw-threaded engagement with each of the shanks, worm teeth on the bushing, a manually operable worm spindle in mesh with the worm teeth, a stop collar rotatable in the casing, a worm spindle engaging the stop collar for turning the latter, an annular gear journaled in the casing in mesh with the shank teeth and adapted to bear outwardly against the stop collar, a spiral spring encircling the die shanks in compression between the head and the gear and projecting the latter against the stop collar, the end portions of the spring being locked respectively with the head and the gear for throwing the latter with the dies to inoperative position when disengaged from the stop collar, a knock-off member reciprocable on the casing secured to the gear and adapted to shift 110 115 120 125 130

the latter against the action of the spring out of engagement with the collar and a manually operable member extending from the gear through the casing with which it is 5 in frictional engagement for moving the gear into interlocked engagement with the stop collar.

In testimony whereof I affix my signature in presence of two witnesses.
